United States Patent Office

Des. 174,916
Patented June 7, 1955

174,916

DISPLAY FIGURE OR SIMILAR ARTICLE

Robert L. Mitchell, Norman, Okla.

Application July 22, 1954, Serial No. 31,549

Term of patent 14 years

(Cl. D34—4)

Fig. 1.

Fig. 2.

Fig. 3.

Fig. 4

To all whom it may concern:

Be it known that I, Robert L. Mitchell, a citizen of the United States and resident of Norman, Oklahoma, have invented a new, original, and ornamental Design for a Display Figure or Similar Article, of which the following is a specification, reference being had to the accompanying drawing, forming a part thereof.

Figure 1 is a front perspective view of a display figure or similar article embodying my new design,

Figure 2 is a front elevation of the same,

Figure 3 is a rear perspective view of the same, and,

Figure 4 is an enlarged perspective view of a head of the figure, removed.

I claim:

The ornamental design for a display figure or similar article, as shown.
